CLAIM

The ornamental design for a motorcycle with tail lights as shown and described.

DESCRIPTION

FIG. 1 is a rear and left side perspective view of a motorcycle with tail lights showing our new design;

FIG. 2 is a detail view of a portion thereof, taken from FIG. 1;

FIG. 3 is a detail rear and right side perspective view thereof;

FIG. 4 is a right side elevation view thereof;

FIG. 5 is a detail view of a portion thereof, taken from FIG. 4;

FIG. 6 is a front elevation view thereof;

FIG. 7 is a rear elevation view thereof;

FIG. 8 is a detail view of a portion thereof, taken from FIG. 7;

FIG. 9 is a top plan view thereof;

FIG. 10 is a detail view of a portion thereof, taken from FIG. 9; and,

FIG. 11 is a bottom plan view thereof.

The broken lines are included for the purpose of showing portions of the motorcycle with tail lights that form no part of the claimed design.

1 Claim, 9 Drawing Sheets
